CLAIM

I claim the ornamental design for a reflective dog safety vest, as shown and described.

DESCRIPTION

FIG. 1 is a right-side view of a reflective dog safety vest shown in use on a dog;

FIG. 2 is another right-side view of the invention;

FIG. 3 is a left-side elevational view of the invention;

FIG. 4 is a front elevational view of the invention;

FIG. 5 is a rear elevational view of the invention;

FIG. 6 is a top plan view of the invention; and,

FIG. 7 is a bottom plan view of the invention.

The broken lines showing a dog in FIG. 1 are included for the purpose of illustrating the invention in use, and form no part of the claimed design.
